UNITED STATES PATENT OFFICE

MARCELLUS DUKE PROVOST, OF SALT LAKE CITY, UTAH

PERMANENT-HAIR-WAVING UNIT

Application filed February 4, 1930. Serial No. 425,829.

This invention relates to an improved permanent hair waving unit of a type similar to an analogous unit now used in the trade and known under the name Duart.

5 Generically stated, the prior art unit mentioned, like the unit herein shown and described, is characterized by a sectional base which functions as a clamp, the sections being hingedly connected together in a manner to 10 permit the bank of hair to be placed between the sections. This base constitutes a mounting for the curling rod around which the free end portion of the hair is tightly wound.

15 In the prior art structure mentioned, the upper face of the sections of the base are formed with outwardly diverging flanges which cooperate in producing a trough-like receptacle in which the curling rod is seated. The curling rod is formed at one end with 20 a ratchet wheel and associated with this is a retention pawl. At the opposite end, the curling rod is provided with a retaining latch for the extremity of the hair.

25 These and other features of the prior art device are well known. The present invention is characteristically distinguishable in that it embodies a structural arrangement of details which allow the curling rod to be arranged offside in such a manner as to permit 30 operation of the curling rod at a point much closer to scalp, the advantage being in that the improved arrangement permits the formation of a wave close to the scalp.

35 The foregoing results and other features and advantages will become more readily apparent from the following description and drawings.

In the drawings:

40 Figure 1 is an elevational view of a unit constructed in accordance with the present invention observing one edge thereof.

Figure 2 is a top plan view of the structure seen in Figure 1.

45 Figure 3 is a view like Figure 2 with the curling rod or mandrel removed.

Figure 4 is an edge view of Figure 3.

Figure 5 is a top view with the sections of the clamping base swung apart.

50 Figure 6 is an enlarged cross section show-

ing the pawl and ratchet mechanism and other associated details.

Figure 7 is a cross section on the line 7—7 of Figure 3.

Figure 8 is a detail view of the curling rod 55 or mandrel on which the hair is wound.

Attention is first invited to Figure 5, wherein it will be seen that the clamping base is composed of a pair of complementary sections distinguished by the reference characters 9 and 10 respectively. These are hingedly connected together at one end through the medium of links 11. At the opposite end, I provide similar links 12 and these links carry a pivoted retaining latch 13 including 60 a retention cam 14 which is adapted for reception in the keeper notch or seat 15.

As seen in Figure 6, each section is of three-ply construction, that is, it is made up of three separate plates thus providing a laminated 70 structure. The sections 10 for instance comprise an inner plate 16 of heat insulation material and a parallel outer plate 17. These are spaced apart by appropriate spacing elements 18 as seen in Figure 1. In addition, 75 there is an intermediate plate 19 whose inner edge is formed into a channel 20 for reception of the tongue of a rubber facing strip 21.

The plate 17 is formed at longitudinally spaced points with right-angularly disposed 80 flanges 22 which as seen in Figure 4 have their upper edges curved and their inner adjacent ends spaced apart to facilitate circulation of air for cooling purposes. Attached to one of these flanges is an arcuate resilient 85 strip 23 having a curled end 24 forming a retention pawl and this is cooperable with the corrugation 25 of the ratchet head seen in Figure 8. This constitutes an integral part 90 of the curling rod or mandrel 26.

At the opposite end of this rod is a pivoted retaining clip 27. Referring again to Figure 6, it will be observed that the sections 9 of the clamp comprises three plates; namely, the inner plate 28, the outer plate 29, and the central or intervening plate 30. The latter plate is formed with a channel 31 receiving and holding in place the remaining rubber spacing strip or buffer 32. Thus when the two sections are swung together as seen in Figure 100

6, the rubber buffers 21 and 32 come together and firmly clamp the strands of the hair therebetween.

Particularly do I wish to emphasize the features of construction of the clamping base.

5 The three plate construction of each section with the spacing elements 18 therebetween, afford open spaces for free circulation of air for cooling purposes. This insures comfort when the unit is in place on the head. The 10 novel assembly of plates facilitates construction by way of simplified manufacture, and affords an economical and convenient and compact arrangement of elements.

There are no flanges on the section 9. The 15 flanges 22 are on the section 10 and they are spaced apart to further facilitate free circulation of air. One of the flanges carries the retention pawl 23 and this permits the entire mandrel or curling rod 26 to be arranged 20 substantially over the section 9 of the base. This disposes the rod off to one side of the center where the two sections seat and insures the formation of a wave at a point much closer to the hair than in prior art units of a 25 similar construction.

In practice it is obvious that the free end portions of the hair, after the hair has been passed between the rubber strips 21, are attached to the curling rod 26 through the medium of the pivoted clamp 27. Then, the 30 pawl 23 is engaged with the corrugated ratchet head 25, and the rod is turned in a well known manner to wind the hair firmly thereon, as represented in Figures 1 and 2.

The spaced flanges 22 constitute stops for preventing accidental displacement of the rod and for aiding in holding it in proper alignment.

40 It is thought that persons skilled in the art to which the invention relates will be able to obtain a clear understanding of the invention after considering the description in connection with the drawings. Therefore, a more 453 lengthy description is regarded as unnecessary.

Minor changes in shape, size, and rearrangement of details coming within the field of invention claimed may be resorted to in 503 actual practice if desired.

I claim:

1. In a permanent hair waving unit of the class described, a pair of elongated, hingedly connected companion sections, latch means 553 at one end of the sections for holding them in abutting relationship, the outer face of one of said sections being free of obstruction and substantially plane, the corresponding face of the remaining section being provided with longitudinally spaced right-angularly disposed stop flanges along its inner longitudinal edge,

2. In a permanent hair waving unit of the class described, a pair of elongated, hingedly 651 connected companion sections, latch means at

one end of the sections for holding them in abutting relationship, the outer face of one of said sections being free of obstruction and substantially plane, the corresponding face of the remaining section being provided with longitudinally spaced right-angularly disposed stop flanges along its inner longitudinal edge, said flanges having their upper edges of curvate configuration and their inner ends spaced apart to facilitate circulation of air therebetween.

3. In a permanent hair waving unit of the class described, a pair of elongated, hingedly connected companion sections, a latch means at one end of the sections for holding them in abutting relationship, the outer face of one of said sections being free of obstruction and substantially plane, the corresponding face of the remaining section being provided with longitudinally spaced right-angularly disposed stop flanges along its inner longitudinal edge, said flanges having their upper edges of curvate configuration and their inner ends spaced apart to facilitate circulation of air therebetween, and an arcuate strip fastened to one of said flanges and terminating in a retention head overlying the first named plane section, said strip constituting a retaining pawl.

In testimony whereof I affix my signature.

MARCELLUS DUKE PROVOST.
